UNITED STATES PATENT OFFICE.

HARRY SUMNER BEST, OF GALVA, ILLINOIS, ASSIGNOR TO JOHN H. BEST & SONS, A FIRM COMPOSED OF CHARLOTTE SUMNER BEST, DON JEWELL BEST, LEON HENSON BEST, AND HARRY SUMNER BEST, OF GALVA, ILLINOIS.

ARM.

Original application filed October 18, 1924, Serial No. 744,313. Divided and this application filed May 25, 1925. Serial No. 32,611.

This case is a division of my co-pending application Serial No. 744,313, filed October 18, 1924.

This invention relates to a novel and improved arm particularly one from which arms may be cut for use with display racks. It is the object of the invention to provide an arm which shall be strong enough to carry the heavy loads imposed thereon and at the same time shall be light in weight, easily made and one which will retain its shape.

In the accompanying drawings in which I have shown a selected embodiment of this invention—

15 Fig. 1 is an elevation of a display rack having an arm constructed of my novel and improved arm.

Fig. 2 is an enlarged transverse section through the arm of Fig. 1.

20 Fig. 3 is an enlarged elevation of the same arm.

Fig. 4 is a section on the line 4—4 of Fig. 2, drawn on an enlarged scale.

In Fig. 1 the arm 1 is pivoted at 2 to a hinge bar 3 secured to a wall plate 4, which in turn is attached to the wall 5, or other suitable support. The outer end of the arm is provided with a roller 6 adapted to keep the arm 1 spaced from other arms which may be mounted upon the hinge plate, as is well known in the art. Each arm is preferably provided with a brace 7 to support it in the correct position, as set forth in my aforesaid co-pending application.

35 Referring now particularly to Figs. 2 and 3, it will be seen that the arm is made from a single sheet of material, such as sheet metal and comprises a vertical stem 8 and a head 9, these forming a T-beam. The stem 8 is in the form of a U having substantially vertical parallel sides 10, these sides being formed by bending the material as at 11. It will be noted that one of the sides 10 is shorter than the other and as shown in Fig. 2 this side, 40 which is the left one, has its upper end bent at 12 at substantially right angles to the vertical portion of the side to form a portion 13 of the horizontally disposed head 9.

The other side 10 is bent at 14 to form a portion extending in substantially the same plane as the portion 13, and is then bent on itself at 15, depressed at 16 between the tops of the sides 10 and it is then carried over the

portion 13, bent at 17 and folded under the portion 13. It will be seen that two flanges 55 are formed, these flanges comprising the head of the T-beam. It has been found that there is a tendency for the portion 13 and the material folded thereover to move longitudinally in respect to each other. This 60 movement results in twisting of the arm and consequent impairing of its rigidity. To avoid this difficulty I secure the portion 13 to the material folded thereover either by spot welding, as indicated at 18 in Fig. 3, 65 by blind punching, or by knurling the contacting surfaces, as shown at 19 in Fig. 4. Any one of the above methods will effectively prevent independent movement of the parts, but I find that the knurling process 70 is the least expensive. It requires no extra operation as some of the forming rolls on the draw bench are knurled and the edges of the material may be conveniently knurled during the forming of the arm.

The result is a T-beam, which is light in weight, but extremely rigid. The sides 10 are held apart a proper distance by the bottom of the U at 11 and also by the depressed portion 16, so as to insure that the arm will 80 keep its shape when in use. The proper strength to resist the bending moment is provided by the depth of the beam.

The flanges formed by the head of the T-beam provide means for supporting rugs or 85 the like, and for this purpose the flanges are apertured at suitable intervals and into these apertures are driven suitable pins 20, these pins being held in place frictionally or by any other suitable means.

90 From the above it will be evident that I have provided an arm from which arms may be cut for use with a display rack, or which may be used for any other structural purpose for which it may be adapted, and which is extremely light in weight, at the same time possessing the requisite strength. Furthermore, my novel and improved arm is very cheaply and very easily made because it is possible to manufacture it on a draw-bench instead of employing a press. Furthermore, it may be easily manufactured in long pieces, from which any desired length may be cut. The vertical stem with its two parallel sides furnishes a ready means for 95 making connections of a piece of arm to 100 105

other elements. All that is necessary is to insert a portion of the other element between the two sides which may then be pressed into engagement therewith, as exemplified in my co-pending application.

I am aware that changes in the form, construction and arrangement of parts may be made without departing from the spirit and without sacrificing the advantages of the invention and I reserve the right to make all such changes as fairly fall within the scope of the following claims.

I claim:

1. A display rack arm in the form of a **T** and formed of one piece of sheet material, the stem of said **T** being in the form of a **U**, the sides of said **U** being bent outwardly to form the head of said **T**, and one of said sides being longer than the other and bent upon itself and overlying the said other side and the material at the head between the sides of the **U** being depressed and in contact with the adjacent bends of the sides of the said **U**, the lateral portions of the material being in contacting relation with each other.

2. A display rack arm comprising a single sheet of material bent into the form of a **T**, the stem of said **T** being in the form of a **U**, one of the sides of said **U** being longer than the other and each side being bent outwardly at right angles from the **U** to form the head of the **T**, the longer of said sides being folded back upon itself, depressed between the sides of said **U**, and overlying and folded under the outwardly bent portion of said shorter side.

3. A display rack arm comprising a single sheet of material bent into the form of a **T**, the stem of said **T** being in the form of a **U**, one of the sides of said **U** being longer than the other and each side being bent outwardly at right angles from the **U** to form the head of the **T**, the longer of said sides being folded back upon itself, depressed be-

tween the sides of said **U**, and overlying and folded under the outwardly bent portion of said shorter side and secured thereto.

4. A display rack arm in the form of a **T** and formed of one piece of sheet material, the stem of said **T** being in the form of a **U**, the sides of said **U** being bent outwardly to form the head of said **T**, and one of said sides being longer than the other and bent upon itself and overlying the said other side, said sides being knurled adjacent their edges to prevent relative longitudinal movement therebetween.

5. A display rack arm in the form of a **T** and formed of one piece of sheet material, the stem of said **T** being in the form of a **U**, the sides of said **U** being bent outwardly to form the head of said **T**, and one of said sides being longer than the other and bent upon itself and overlying the said other side and folded thereunder, said sides being knurled adjacent their edges to prevent relative longitudinal movement therebetween.

6. A display rack arm comprising a single sheet of material bent into the form of a **T**, the stem of said **T** being in the form of a **U**, one of the sides of said **U** being longer than the other and each side being bent outwardly at right angles from the **U** to form the head of the **T**, the longer of said sides being folded back upon itself, depressed between the sides of said **U**, and overlying and folded under the outwardly bent portion of said shorter side, said sides being knurled adjacent their edges to prevent relative longitudinal movement therebetween.

7. An arm for a display rack, comprising an elongated unitary member **T**-shaped in cross section, the stem of the **T** being **U**-shaped and the head of said **T** formed of contacting lateral portions of said member, and the said head having a depression extending into the said stem.

HARRY SUMNER BEST.
